 Lombardi Knitting Machine Co., Inc., New
 York, N. Y., a corporation of New York

Application November 17, 1939, Serial No. 304,918

25 Claims. (Cl. 66—201)

This invention relates to knitted fabric.

An object of the invention is to provide knitted fabric having unusual design effects.

Another object is the provision of various improved types of fabric.

Other objects of the invention will in part be obvious and will in part appear hereinafter.

The ordinary types of knitted design fabric depends for its pattern entirely on the use of yarn 10 of various colors or characters. Such design fabrics, while highly desirable for many purposes and embodying in some instances a wide variety of design, do not, in essence, differ widely in design effect from the design effects of woven design 15 fabrics or printed fabrics. Knitted fabrics are not, however, subject to such inherent limitations of design as are woven design fabrics and printed fabrics, and the present invention is accordingly directed to certain types of knitted design fabrics 20 wherein unusual design effects may be obtained regardless of whether or not the yarns employed are of different color or character, and, also, to knitted fabrics wherein various knitted portions of yarn are interconnected in particularly effective 25 and/or attractive manners.

In accordance with the invention warp yarns are employed in the fashioning of such fabrics whereby wide variability in design effects may be secured. Such yarns may be employed in only 30 those portions of the fabric wherein design effects are desired or may be present thruout the entire fabric if desired; the invention in certain of its aspects contemplating the provision of fabric composed entirely of warp yarns, each of 35 at least a plurality of such yarns extending back-and-forth coursewise of the fabric in at least a portion of its extent. Fabrics of the latter character may be of relatively light weight and may 40 be economically produced, and at the same time may embody widely varying design formations whether the design depends upon a difference of color or character of the yarns or on differences in knitting in certain portions or on both.

45 Among the features of the present invention are the provision of design portions resulting from knitting of yarns in a special manner as by knitting of certain yarns in additional courses than other of the yarns to provide bulge or other 50 effects; the knitting of individual yarns of such manner that ends of successions of loops are drawn toward each other to provide rope-like or other effects; and the provision of fabrics wherein some or all of the portions of the fabric are 55 composed only of warp yarns some or all of which

extend back-and-forth over a substantial number of wales.

The invention accordingly comprises an article of manufacture possessing the features, properties, and the relation of elements which will be 5 exemplified in the articles hereinafter described and the scope of the application of which will be indicated in the claims.

For a fuller understanding of the nature and objects of the invention reference should be had 10 to the following detailed description taken in connection with the accompanying drawings, in which:

Figure 1 is a somewhat diagrammatic rear view 15 (looking at the inside of the fabric as it is formed in a circular machine, for example) of one form of fabric embodying the invention;

Fig. 2 is a sectional view along the line 2—2 of Fig. 1;

Fig. 3 is a somewhat diagrammatic front view 20 of a modified form of fabric;

Fig. 4 is a sectional view along the line 4—4 of Fig. 3;

Fig. 5 is a schematic rear view of another modified form of fabric embodying invention; 25

Fig. 6 is a similar view of still another modified form of fabric;

Fig. 7 is an enlarged-scale detailed view of the portion of the fabric outlined in dot-and-dash lines at the left-hand side of Fig. 6; 30

Fig. 8 is a similar view of the portion of the fabric outlined in dot-and-dash lines at the right-hand side of Fig. 6;

Fig. 9 is a view similar to Figs. 5 and 6 showing 35 an additional modification;

Fig. 10 is a similar view showing still another modification;

Fig. 11 is a detail rear view of a portion of a further modified form of fabric; and

Fig. 12 is a fragmentary view looking upwardly 40 from the bottom of Fig. 11.

In the form of construction shown in Figs. 1 and 2, there is illustrated a portion of a fabric embodying the usual coursewise-extending weft yarn 4 of which much of the body of the fabric 45 is composed in the present instance; and warp yarns which provide design effects in the present instance, and three of which are shown at 5, 6, and 7. These yarns may all be of the same color and character, or may be of different colors or 50 characters as may be desired in a particular case. For example, the body yarn 4 may be white yarn, the yarn 5 red yarn, the yarn 6 blue yarn, and the yarn 7 green yarn. The portion of the fabric shown comprises wales a thru o, and the 55

weft yarn 4 provides courses 8 thru 20. In the present instance the body yarn is knitted in wales a, b, h, i, k, l, n, and o; the warp yarn 5 extending back-and-forth thru wales c-g, and being 5 knitted in one course as it extends in one direction and in a succeeding course as it extends in the other direction, the weft yarn 4 extending in an undulating manner thru these wales without knitting, being caught therein under the sinker 10 loops of the yarn 5, in the present instance, in such manner that it lies against the rear of the fabric. This may be performed by causing the yarn to extend behind one or more needles and then in front of one or more needles, as for example 15 by partially raising certain spaced latch needles or spaced groups of latch needles in a latch-needle machine, as exemplified for instance in various of my patents, including Patents Nos. 1,541,230 and 1,728,293. The yarn 4 also extends 20 under those portions of the yarn 5 which extend vertically across a wale, as exemplified at 21 and 22. By thus extending under portions of the yarn 5, the weft yarn holds wales c thru g in the fabric. The yarn 6 is knitted in wale j and extends 25 vertically behind the weft yarn as exemplified at 23 and 24, so as to be held into the fabric, the weft yarn floating across wale j as indicated. The yarn 7 is knitted in wale m and is held in the fabric in the same manner as the yarn 6. 30 At certain points in the portion of the fabric exemplified, the yarn 5 and 7 are knitted in supplemental courses to provide thickened effects in the nature of bulges. The yarn thus knitted is connected with the fabric at the walewise ends 35 of the bulges, but not at the coursewise ends thereof. One such bulge which is provided by the warp yarn 5 is exemplified at A. In the formation of this bulge, the loops of the weft yarn 4 in course 12 may be held on the needles while 40 successive supplementary courses of the yarn 5 is knitted to provide a series of coursewise successions of loops. In the present instance eight such successions of the yarn 5 are knitted while the needles knitting the yarn 4 are inactive, so 45 that a broad bulge, the outline of which will be seen clearly from Fig. 2, is provided. As will be seen, the bulge in substance includes these eight rows of the yarn 5, as well as a ninth row cast at the same or nearly the same time that the 50 course 13 of the weft yarn 4 is cast; the rows of the bulge being indicated at 12a-12i in Fig. 2. The bulge in the present instance is five wales wide thruout its extent. Another such bulge 55 which is provided by the warp yarn 5 is exemplified at B. In the formation of this bulge, the loops of the weft yarn 4 in course 16 may be held on the needles while successive supplementary rows 16a-16e of the yarn 5 is knitted to provide a series of successions of coursewise 60 extending loops, which, together with the row 16f, which is cast at the same or nearly the same time as the weft yarn 4 in course 17, provide the five-wale bulge B, which is, as will be seen from Fig. 2, narrower than the bulge A. As 65 will be seen, rows 12b-12h and 16b-16e are entirely unconnected with the fabric coursewise thereof, being bound to the fabric by the end rows 12a and 12i in the case of bulge A, and 16a and 16f in the case of the bulge B. Likewise, 70 the yarn 7 is formed into bulges C and D which are similar to the bulges A and B, and are similarly formed, except that the bulges C and D are only one wale in width. These bulges, like the bulges A and B, provide walewise successions 75 of loops which are unconnected with the body

of the fabric except by the end loops. As will be seen, the yarn which does not form the bulge—this yarn being the weft yarn 4 in the present instance—serves to interconnect the portions of the fabric at the upper and lower ends of the bulges at points laterally of the bulges. The 5 yarn 6 provides no bulges in portion of the fabric exemplified, and its showing indicates that a warp yarn may be present without being knitted to provide a curled portion, such for example as 10 bulge, in the fabric. It may, however, be formed into bulges or otherwise curled portions in other parts of the fabric is desired.

In Figs. 3 and 4, there is illustrated a portion 15 of a fabric embodying a somewhat different type of bulge. This bulge, shown at E, is longer than the bulges A and B, and, in order to prevent the fabric from flattening the center wales of the bulge by drawing it apart in a walewise direction, the portions of the fabric above and below 20 the bulge are, in accordance with the invention, interconnected intermediate of the sides of the bulge as well as at the sides of the bulge. The bulge, in this instance, is even narrower than the bulges B and D, but it will be appreciated that 25 long broad bulges may be employed as well as short narrow bulges, short broad bulges, and long narrow bulges in accordance with the various aspects of the invention. The fabric of Figs. 3 and 4 is generally similar to the fabric shown in 30 Figs. 1 and 2, the portion illustrated comprising weft yarn 36 which extends coursewise thruout the extent of the fabric in the present instance. The portion of the fabric shown comprises wales a' thru m' and courses 28 thru 35. The yarn 35 36 is knitted thruout wales a', b', e', i', l', and m'. The loops in the remaining wales are formed by a warp yarn 37, which extends back-and-forth across wales c'-k'. The weft yarn 36 extends across wales c' and d', f'-h', and j' 40 and k', without being knitted. In all of its courses except course 32 it is caught under portions of the knitted warp yarn as it extends past these wales, being caught in the present instance under the sinker loops between wales c' and d', 45 under the sinker loops between wales f' and g', and between wales g' and h', and under the sinker loops between wales j' and k', and thus tending to hold the fabric together. The warp yarn as it extends back-and-forth floats past 50 wales e' and i' without being knitted, extending at the rear of the fabric at these points, and additionally serving to hold the fabric together by providing an interwoven effect in those courses which are below and above the bulge. 55

In the formation of the bulge exemplified at E, the loops of the weft yarn 36 in course 32 may be held on the needles while a single supplementary row of the yarn 37 is knitted. In addition, in the knitting of course 32, the weft 60 yarn is left entirely free of the needles in wales c', d', f', g', h', j', and k', so that this yarn, instead of holding the fabric flat, will float freely from wale b' to wale e', from wale e' to i', and from wale i' to wale l' without connection with 65 the yarn 37. Thus in each wale of the yarn 37 there are three loops which are not held flat in the fabric, and which provide a bulge consisting of rows 31a, 32a, and 32b. In these rows, since they are free from the holding effect of 70 the weft yarn 36, the loops tend to draw together, particularly in the center row 32a, so that the loop in the wale d' tends to draw close to the loop in wale f' and the loop in wale h' tends to draw close to the loop in wale j', thus 75

providing a six-wale bulge which extends over eight-wales, although it tends to draw inwardly somewhat in a coursewise direction.

As above indicated, the invention in certain of its aspects contemplates the provision of fabric composed entirely of warp yarn. In Fig. 5 there is exemplified a portion of a fabric wherein a number of warp yarns extends back-and-forth to provide a number of zones in the fabric, these zones being held together by a zigzag over-lap at their edges. In the present instance certain of these warp yarns are knitted to provide bulges, and in addition there is another warp yarn which appears in a single wale of one of the zones and which is knitted to provide bulges. The zones in the portion shown are indicated at I, II, III, and IV, which are formed respectively of yarns 40, 41, 42, and 43; parts of a yarn 45 being shown at the left of Fig. 5, and parts of a yarn 46 being shown at the right of Fig. 5. A yarn 47 is knitted in one wale of the zone IV. In the lowermost course of Fig. 5, the yarn 40 is knitted in the first five wales, the yarn 41 in the next five wales, the yarn 42 in the next five wales, the yarn 43 in the next 10 wales, and the yarn 46 in the last two wales. In the next course from the bottom, the yarn 45 is knitted in the first wale, the yarn 40 in the next five, the yarn 41 in the next five, the yarn 42 in the next five, the yarn 43 in the next 10 wales, and the yarn 46 in the last wale. In the third course from the bottom the arrangement of the lowermost course is repeated, and the zig-zag arrangement is thereafter continued, thus giving a one-wale over-lap whereby, in the first 30 6th, 11th, 16th and 26th wales, yarns from alternate zones are interknitted so as to securely bind the different zones together. The yarn 47 is incorporated in zone IV in the same manner that the yarns 6 and 7 are incorporated in Fig. 1, the 40 yarn 47 extending vertically behind the floats of the yarn 43, except where the yarn 47 is formed into bulges.

Suitably spaced bulges are formed in zones II and III of the fabric, each of these bulges in the 45 present instance comprising six rows, including the row corresponding to the omitted portion of the course in the flat fabric. The alignment of the wales of the bulge with respect to the yarn in adjacent zones corresponding to what the 50 alignment of the loops would be if the bulge did not occur. A portion of one of these bulges is shown at F in zone II beneath the lowermost course shown. Another such bulge is shown at G in zone III curling about the space which would 55 be occupied by the fourth course from the bottom if this were continuous. In zone II there is shown a bulge H at the eighth row from the bottom; and in zone III a bulge at the twelfth row from the bottom of the figure. Each of these bulges 60 is five wales wide. The yarn 47 is formed with bulges in coursewise alignment with each of the bulges F, G, H, and I, these bulges each having a number of loops corresponding with the number of rows in the bulges in zones II and III.

In Figs. 6, 7, and 8 there is shown a form of construction wherein portions of warp yarns are knitted to form a walewise series of coursewise successions of loops with the loops intermediate 70 the end loops in the coursewise successions unconnected with yarn disposed laterally of said portions, and with the end loops of the successions connected by extents of yarn which are shorter than their successions so that the portions will curl to provide thickened effects in the

nature of ropes. The portion of the fabric exemplified in Fig. 6 is divided into five zones. In each of zones I, III, and V, a weft yarn 50 which in the present instance extends coursewise throughout the extent of the fabric is knitted throughout 5 four wales. In zone II, the weft yarn 50 is unknitted, but five wales of a warp yarn 51 which extends back-and-forth throughout the portion of its extent shown are provided. In the 3rd, 4th, and 5th courses from the bottom and in the 2nd, 10 3rd, and 4th courses from the top, this yarn is knitted in one direction in each course, but is floated in the other direction, the weft yarn 50 being caught under the sinker loops of the knitted warp yarn 51 so as to lie predominantly at the 15 rear of the fabric in the same manner as the yarn 4 is caught under the loops of the yarn 5 in Fig. 1. This arrangement is illustrated in the lowermost part of Fig. 7, wherein the yarn 51 is shown knitted in one direction as, at 52 and 53, and 20 floated in the other direction, as at 54 and 55, and the weft yarn 50 is shown caught under the sinker loops of the knitted row 53 at 56 and 57.

In the middle courses of zone II of Fig. 6, the 25 yarn 51 is so knitted as to provide a rope-like effect J, the construction being more readily understood by references to Fig. 7 in which it will be seen that in the course above the lowermost part of the figure the weft yarn 50, instead of being caught under the sinker loops so as to hold 30 the warp yarn 51 flat, is floated to provide a plurality of extents 58 which extend under the floats 59, 60, 61, 62 and 63 of the warp yarn as it extends in the direction in which it is not knitted. As the warp yarn extends upwardly from the 35 course 53, these floats tend to pull the end loops of the five-loop successions of knitted warp yarn together, the float 59 being shorter than the float 55, and the float 60 still shorter, etc., until the float 63 is substantially in the form of a sinker 40 loop. Since the floats 59—63 extend at the rear of the floats 58 of the weft yarn, the end loops of the five-wale successions of loops are connected 45 with the weft yarn 50 but the three intermediate loops are unconnected with the weft yarn 50 and are free to curl around to provide a rope-like effect. In the top course, and the two lowermost courses of Fig. 6, the lower and upper parts, respectively, of additional rope-like effects are 50 shown.

In zone IV of Fig. 6, there is provided a warp 55 yarn 64. The arrangement in the 3rd, 4th and 5th courses from the bottom and the 2nd, 3rd, and 4th courses from the top, is the same as in zone II, the yarn 64 being knitted in five wales in one direction and floated in the other direction, and the weft yarn 50 extending in an undulating manner at the rear of the knitted warp yarn and being caught under the sinker loops 60 of the warp yarn. In the middle of the zone, there is formed a curled portion K of rope-like conformation similar to the rope-like portion J in the middle of zone II, except that the weft yarn 50 is knitted along with the yarn 64 in the right hand wale so as to provide a plated effect 65 as illustrated at 65 in Fig. 8. In the upper course and the two lower courses of zone IV of Fig. 6 parts of similar rope-like effects are shown.

In Fig. 9 there is shown a portion of a fabric 70 wherein weft yarn 66 is unknitted, wherein warp yarns 67, 68, and 69 are knitted in zones I, III, and V to provide stripes which are five wales wide, and wherein warp yarns 70 and 71 are knitted in zones II, and IV to provide five-wale 75 rope-like effects L and M which never flare as

does the yarn 51 at the bottom of Fig. 7, but which thruout their extent correspond to the uppermost part of Fig. 7, so that there is a continuous gap in the fabric between the ropes in zones II and IV and the stripes in zones I, III, and V. The arrangement of the yarn 67 in zone I is similar to the arrangement of the yarn 5 in the uppermost part of Fig. 1, for example; the arrangement of the yarns 68 and 69 in zone III 10 and V, respectively, being similar to the arrangement of the yarn 67 in zone I. The weft yarn 66 extends only thru portions of the walewise extent of the fabric. In the upper center of the fabric, there are shown four strands of the weft 15 yarn 66 which extend at the rear of the fabric in zones I, III, and V in an undulating manner and are caught under the sinker loops of the yarn 67, 68, and 69, in the same manner that the yarn 4 is caught under the sinker loops of 20 the yarn 5 in Fig. 1. These four strands are caught into the ropes formed by the yarns 70 and 71 in the same manner as the strands 58 are caught into the ropes shown in Fig. 7. In the lower center of Fig. 9 there are shown five 25 strands of weft yarn 66 and which similarly extend at the rear of the fabric caught under sinker loops of the yarn 67, 68 and 69 in zones I, III, and V, in the same manner that the yarn 4 is caught under the sinker loops of the yarn 5 in 30 Fig. 1. However, instead of extending directly across zones II and IV, in the present instance, these five strands are gathered together where the upper two strands extend downwardly and the lower two strands extend upwardly, and the 35 group of strands are caught in zones II and IV together. Except for the grouping, they are caught into ropes formed by the yarns 70 and 71 in the same manner that the strands 58 are caught into the fabric in Fig. 7. As will be ap- 40 parent other strands of weft yarn caught in the different zones in one of the above manners, for example, may be present in the fabric above and below the portion of the fabric illustrated in Fig. 9. In this manner, the fabric is held together 45 so that the various warp yarns in conjunction with the weft yarn provide a distinctive fabric having a highly attractive lace-like effect.

As above indicated various types of fabric embodying the invention may be formed without the 50 provision of weft yarn. In Fig. 10 there is indicated a portion of a fabric wherein rope-like effects are provided but wherein weft yarn is not present. The portion illustrated comprises three zones, II, III and IV, and portions of two other 55 zones, I and V, and the fabric is composed of a plurality of warp yarns each of which, in the portion of the fabric illustrated, is formed into a walewise series of coursewise successions of loops. As exemplified, the portion of fabric illustrated 60 is composed of a warp yarn 71' appearing primarily in zone I, a warp yarn 72 appearing primarily in zones II, a warp yarn 73 appearing primarily in zone III, a warp yarn 74 appearing primarily in zone IV, and a warp yarn 75 appearing primarily in zone V. In the center of the fabric, the yarns 72, 73 and 74 are shown formed into rope-like effects N, O, and P, having flared ends, and constructed similarly to the rope-like effect shown in the center of zone II of Fig. 6, 65 and illustrated in further detail in Fig. 7, except that no weft yarn is present. In the fourth course from the top of Fig. 10, and in the fifth course from the bottom of Fig. 10 the yarns 72 and 74 are knitted only in three wales and yarn 75 71', 73 and 75 are knitted in seven wales, so as to

extend into the outer wales of zones II and IV to be interknitted walewise with the yarn 72 or 74, as the case may be, thus tying the yarns in the different zones together and holding the fabric flat at these points. It is to be noted that in the 5 top course and in the two bottom courses of Fig. 10, the ends of the rope-like effects similar to those shown in the center of the figure are shown. In the second course from the top and the third course from the bottom, the yarns 71', 10 73 and 75 are knitted in seven wales and the yarns 72 and 74 are knitted in only one wale so as to assist in tying together the different yarns of the fabric and the holding of the fabric flat at these points, and also to give desirable de- 15 sign effects when, for example, the odd-numbered yarns are one color, for instance blue, and the even numbered yarns are of another color, for instance white. In the present instance, each of the yarns composing the fabric is knitted only 20 in one direction and is floated in the other direction, as in the case of the yarns 51 and 64 in zones II and IV of Fig. 6. It will be appreciated, however, that, if desired, a yarn, instead of being floated in the second, third, and fourth 25 wales from the top and the third, fourth, and fifth wales from the bottom as it extends in the said other direction, may be caught under suitable sinker loops of the knitted yarn, if desired, or may be otherwise caught without knitting, or 30 even knitted in certain instances.

In Figs. 11 and 12 there is exemplified a form of fabric having a design portion wherein a bulge and a rope-like effect are combined. The portion of the fabric illustrated in Fig. 11 embodies 35 courses 76—83 and wales r—z. Weft yarn 84 is knitted in wales r, x, y, and z, and a warp yarn 85 extends back-and-forth thruout wales s—w, being knitted as it extends in one direction and being floated as at 86 as it extends in the other 40 direction. The weft yarn 84 in all its courses is caught under sinker loops of the warp yarn 85 so as to extend in an undulating manner across wales s—w and to hold the fabric together. Between the courses 79 and 81 the warp yarn 84 45 is knitted to provide ten additional courses which, together with the courses corresponding to the course 80, provides an eleven-row five-course bulge. This bulge differs from the bulges of Figs. 1—5, however, in that the warp yarn 84 is only 50 knitted in one direction, being floated in the other, so that the floats will tend to draw the edges of the bulge together to provide a rope-like effect in the bulge, the construction of this 55 rope-like portion being similar to that of Fig. 7 with the exception that the weft yarn does not extend therethru as in Fig. 7. As in Fig. 7, the floats tend to become shorter and shorter until they are similar to the sinker loop near the center of the bulge, these floats being indicated at 86a—86k. There is thus provided a design effect which curls in both a coursewise and wale- 60 wise direction.

Since certain changes may be made in the 65 above articles and different embodiments of the invention could be made without departing from the scope thereof, it is intended that all matter contained in the above description or shown in the accompanying drawings shall be interpreted as illustrative and not in a limiting sense.

It is also to be understood that the following 70 claims are intended to cover all of the generic and specific features of the invention herein described, and all statements of the scope of the 75

invention which as a matter of language might be said to fall therebetween.

I claim:

1. Knitted fabric comprising a warp yarn which extends back-and-forth in a coursewise manner in at least a portion of its extent and which in at least a certain part of said portion is in the form of one or more successions of loops bulging in at least one direction to provide thickened effects in the fabric, and other yarn knitted in certain parts of the fabric disposed laterally of the first-mentioned yarn, said first-mentioned yarn being arranged with the loops intermediate the end loops of a bulging succession having no direct attachment to said other yarn.

2. Knitted fabric comprising yarn which extends coursewise thruout the extent of the fabric and which is knitted at least in portions of said extent, and warp yarn at least certain portions of which are in the form of successions of loops running in at least a walewise direction and arranged with the loops intermediate the end loops in at least certain of the successions having no direct attachment to the coursewise-extending yarn.

3. Knitted fabric comprising a plurality of strands of yarn each occupying a limited part of the coursewise extent of the fabric, each of at least a plurality of such strands being formed into a walewise series of coursewise successions of loops, at least one of said strands at at least a portion of its extent being formed into a series of successions of loops running in a walewise direction and being arranged with certain of said walewise successions unattached to the others of said strands and bulging from the fabric.

4. Knitted fabric comprising warp yarn which extends back-and-forth in a coursewise manner in at least a portion of its extent, and other yarn knitted at parts of the fabric disposed laterally of said portion, said warp yarn being so incorporated into the fabric at at least a part of said portion as to be substantially free of binding effect of said other yarn and curling in at least one direction to provide thickened effects in the fabric.

5. Knitted fabric comprising yarn which extends coursewise thruout the extent of the fabric, and warp yarn at least certain portions of which are so incorporated into the fabric as to be substantially free of binding effect of the coursewise-extending yarn and curling in at least one direction to provide thickened effects in the fabric.

6. Knitted fabric comprising a plurality of strands of yarn each occupying a limited part of the coursewise extent of the fabric, each of at least a plurality of such strands being formed into a walewise series of coursewise successions of loops, at least one of said strands at at least a portion of its extent being formed into a series of successions of loops running in a walewise direction and arranged with end loops of at least certain thereof drawn together to cause the same to bulge.

7. Knitted fabric comprising yarn which extends coursewise thruout the extent of the fabric and which is knitted at least in portions of said extent, and warp yarn at least certain portions of which are in the form of successions of loops running in at least a walewise direction and arranged with the loops intermediate the end loops in the walewise successions unattached to the coursewise-extending yarn.

8. Knitted fabric comprising yarn which ex-

tends coursewise thruout the extent of the fabric and which is knitted at least in portions of said extent, and warp yarn at least certain portions of which are in the form of successions of loops running in at least a walewise direction and arranged with the loops intermediate the end loops in the walewise successions unattached to the coursewise-extending yarn, said portions being held to the fabric by the end loops of the walewise successions.

9. Knitted fabric comprising yarn which extends coursewise thruout the extent of the fabric and which is knitted at least in portions of said extent, and warp yarn at least certain portions of which are in the form of successions of loops running in at least a walewise direction and arranged with the loops intermediate the end loops of the coursewise successions unattached to the coursewise-extending yarn.

10. Knitted fabric comprising yarn which extends coursewise thruout the extent of the fabric, and warp yarn at least a portion of which embodies successions of loops running in a coursewise direction and arranged with the loops intermediate the end loops in the successions unattached to the coursewise extending yarn, said warp yarn in at least a part of said portion extending back-and-forth and being knitted one way to provide such successions while being floated the other way so as to draw the ends of the successions together.

11. Knitted fabric comprising yarn which extends coursewise thruout the extent of the fabric, and warp yarn at least a part of which extends back-and-forth to provide a series of successions of loops, the loops of said successions being interknitted and the end loops of said successions being drawn together at their ends, certain of said successions being unconnected with said coursewise-extending yarn and other of said successions being connected with said coursewise-extending yarn.

12. Knitted fabric comprising yarn which extends coursewise thruout the extent of the fabric, and warp yarn at least a part of which extends back-and-forth to provide a series of successions of loops, the loops of said successions being interknitted and the end loops of said successions being drawn together at their ends to pull the successions back upon themselves, at least certain of said successions being connected at their end loops to the coursewise-extending yarn and the walewise ends of the series of successions being knitted to the fabric.

13. Knitted fabric comprising a portion embodying warp yarn knitted to provide a plurality of wales and a plurality of contiguous rows of loops, said fabric embodying additional portions of knitted yarn disposed walewise of the first-mentioned portion and further portions having a lesser number of loops walewise of the fabric than the aforesaid portions and connecting said additional portions to cause the first-mentioned portion to bulge.

14. Knitted fabric comprising a bulging portion embodying one or more wales of knitted warp yarn, additional portions of knitted yarn disposed walewise of the first-mentioned portion, and further portions of knitted yarn embodying a lesser number of loops walewise of the fabric than the aforesaid portions, and connecting said additional portions laterally of said first-mentioned portion.

15. Knitted fabric comprising a portion consisting of a plurality of wales and a plurality of rows of certain knitted yarn, and additional por-

- tions of knitted yarn disposed walewise of the first-mentioned portion and embodying other yarn running coursewise of the fabric and also said certain yarn of which said first-mentioned portion is composed, said first-mentioned portion being unconnected with other knitted loops except at the walewise ends of said first-mentioned portion, and said additional portions being connected laterally of said first-mentioned portion 10 as well as by said first-mentioned portion.
16. Knitted fabric comprising a portion consisting of a plurality of wales and a plurality of rows of certain knitted yarn, and additional portions of knitted yarn disposed walewise of the 15 first-mentioned portion and comprising said certain yarn and other yarn, said first-mentioned portion being unconnected with the remainder of said fabric except in two courses disposed at the walewise ends of said first-mentioned portion, 20 and said additional portions being connected laterally of said first-mentioned portion as well as by said first-mentioned portion.
17. Knitted fabric comprising yarn knitted to form a plurality of wales and rows of loops, each 25 of at least certain of said rows being substantially tubular with the end loops thereof interconnected by an extent of the same yarn which is shorter than its row.
18. A knitted fabric comprising weft knitted 30 yarn and warp yarns, each of at least a plurality of said warp yarns comprising a portion containing a walewise-extending series of loops with the end loops of said portion caught by weft yarn and at least the majority of the intermediate loops 35 connected with the weft yarn or with the other of said warp yarns.
19. A knitted fabric comprising weft yarn and warp yarns, each of at least a plurality of said warp yarns comprising a portion containing a 40 walewise-extending series of short coursewise rows of loops with the end rows of said portion caught by weft yarn and intermediate rows unconnected with the weft yarn or with the other of said warp yarns.
45. 20. A knitted fabric comprising weft yarn and warp yarns, a plurality of said warp yarns being knitted to provide a plurality of walewise-extending plural-wale strips connected at at least one of their ends by weft yarn and unconnected intermediate their ends, the weft yarn being absent from a portion of the fabric containing said strips.
21. A knitted fabric comprising a portion including a plurality of walewise and coursewise 5 successions of loops, each of certain of said coursewise successions having its end loops drawn together in the knitting thereof so that the succession will bend back upon itself, and each of other of said coursewise successions being substantially flat.
22. A knitted fabric formed of a plurality of 10 yarns and comprising a portion composed of warp yarn knitted to form a plurality of wales and rows of loops, said portion being free of loops of 15 other yarn, the end loops in at least each of certain of said rows being interconnected by an extent of said warp yarn which is shorter than its row.
23. A knitted fabric including a walewise succession of loops of yarn which succession is connected with the fabric only thru its end loops and in which the end loops are drawn together so that the succession will bend back upon itself, said 20 yarn extending into adjacent portions of the 25 fabric.
24. A knitted fabric comprising a warp yarn 30 extending back and forth in a portion of the fabric of limited coursewise extent and incorporated in the fabric in such manner as to lie flat in certain coursewise extents thereof, said yarn being incorporated in certain other of its coursewise extents to form a series of coursewise and walewise successions of loops with the central loops of the 35 coursewise successions projecting to form a bulge.
25. A knitted fabric comprising a warp yarn 40 extending back and forth in a portion of the fabric of limited coursewise extent and incorporated in the fabric in such manner as to lie flat in certain coursewise extents thereof, said yarn being incorporated in certain other of its coursewise extents to form a series of coursewise and walewise successions of loops with the end loops of the 45 walewise successions drawn together so that the walewise successions will bend back upon themselves.

VINCENT LOMBARDI.
